UNITED STATES PATENT OFFICE

2,683,361

JET OPERATED REFRIGERATOR

Raymond Ridgley, Detroit, Mich.

Application July 24, 1952, Serial No. 300,678

3 Claims. (Cl. 62—117.65)

1

This invention relates to a jet operated refrigerator and particularly to a jet operating system having means to prevent vapor lock of the driving pump.

In the operation of jet operated refrigerators there has been difficulty because of the entrainment of gas in the pump or the formation of gas therein to cause a vapor lock in the driving system and also difficulty has been encountered because of backflow of fluid refrigerant into the evaporating coils on a failure of the jet.

The present invention provides a pumping system so arranged that no gas can be entrapped in the pumping system so that the jet may be continuously operated and the utilization of a check valve between the evaporator and the suction jet chamber so that the evaporator will continue to operate for an interval in the event the jet should be shut down.

This is accomplished according to the invention by providing a receiver having a quantity of liquid refrigerant therein and a centrifugal pump completely immersed in the liquid refrigerant so that no gas can be picked up by the pump. The condensing device for returning the refrigerant to the receiver is provided with a sloping header so that a liquid seal is provided between the condenser and the receiver so that gases are separated from the liquid being returned to the receiver. The device further utilizes the use of a shunt valve around the evaporator control valve so that liquid refrigerant may be passed through the evaporating coil to defrost the same.

It is accordingly an object of the invention to provide an improved jet operated refrigerator.

It is a further object of the invention to provide a jet operated refrigerator having a completely immersed pump.

It is a further object of the invention to provide a refrigerating system having a vapor trap between the condenser and the receiver.

It is a still further object of the invention to provide a bypass valve for flooding the evaporator with liquid refrigerant to defrost the same.

It is a further object of the invention to provide a check valve between the evaporating coil and the condensing chamber to prevent backflow of liquid refrigerant thereto.

Other objects and many of the attendant advantages of the present invention will be apparent from the following detailed description taken in conjunction with the accompanying drawing in which the figure is a schematic illustration of a jet operated refrigerator according to the invention.

2

In the exemplary embodiment of the invention, a receiver tank 10 has an electric motor 12 mounted therein which has a shaft 14 driving a centrifugal pump 16 which is completely immersed in a quantity of liquid refrigerant 18 received in the receiver tank 10.

The pump 16 delivers liquid refrigerant to a pressure line 20 which in turn supplies liquid refrigerant to a nozzle 22 which is received in a suction housing 24 and has a return connection 26 connected to a top header 28 of a condenser having a plurality of condensing tubes 30 provided with cooling fins 32. The condensing tubes 30 are connected into a return header 34 which is connected into the receiver 10 by means of a conduit 36.

The return header 34 is inclined with respect to the horizontal so that one end 38 is at a considerably lower level than the other end 40. The conduit 36 is connected into the lower end 38 and connects into the receiver 10 at a point 42 materially below the normal level of refrigerant 18 in the container 10. The upward slope of the header 34 is sufficient that the top end 40 is above the liquid level of the refrigerant 18 in the container 10 so that a portion of the header 34 is flooded as well as the lower ends 44 of a portion of the tubes 30.

The refrigerating system per se comprises an evaporating coil 50 to which is connected a supply line 52 which connects into the container 10 at a point adjacent the bottom thereof so that the entrance 54 of supply line 52 will be constantly below the level of the liquid in the container 10. The evaporator coil 50 is connected into the chamber 24 by means of a suction line 56 so that the jet 22 constantly entrains the gas or other material coming through the line 56 into the chamber 24 so that a suction is supplied to the evaporator 50 to cause fluid from the container 10 to flow through the supply line 52 into the evaporator 50. A throttling valve 60 is supplied in series between the supply line 52 and the evaporator 50. The control valve 60 may be either a capillary tube as is well known or may be any type of mechanically or otherwise operated control valve for controlling or throttling the flow of liquid into the evaporator 50.

The check valve 62 having a control ball valve 64 is placed in the suction line 56 so that on the failure of the jet 22 to produce suction in the line 56 the spring 66 will seat the valve 64 to close the suction line 56 to prevent reverse flow of the gas or liquid from the return line 26 into the suction line 55 and thus cause flooding of

the evaporator. Preferably a bypass valve 70 is connected in shunt with the control valve 60 so that the valve 70 may be opened to permit a flow of liquid refrigerant from the container 10 into the evaporator 50 to flood the same and cause defrosting thereof.

In the operation of the refrigerator according to the invention, the pump 16 will be driven by the motor 12 through the driving connection 14 to impel pressure fluid through the conduit 20 10 through the nozzle 22 to entrain gas or other material in the chamber 24 and drive the same into the header 28. The valve 62 will be operated in conjunction with the control valve 60 to cause a continuous or intermittent flow of 15 fluid through the supply line 52 into the evaporator 50 where the gases produced will be drawn off through the suction line 56 and commingled with the pressure fluid being delivered through the nozzle 22. The gases and the liquids will be separated in the header 28 with the liquids falling rapidly through the tubes 30 while the gases will be retained in the tubes 30 and condensed into a liquid by heat exchange through the fins 32. The liquid flooding the lower portion of the header 34 provides a liquid seal between the condenser and the receiver 10 so that only liquid will flow through the return conduit 36 to maintain the liquid level in the receiver 10 while any gases falling through the tubes 30 will rise to 30 the end 40 of the inclined header 34 so that the gases will continuously move upwardly into the condenser tubes 30 to be condensed therein.

It will accordingly be seen that the present invention provides a jet system in which there is little or no chance of vapor lock of the jet nozzles and in which the refrigerant will be completely condensed before returning to the receiver and in the event of inoperative condition of the nozzle the evaporator will be maintained in cooling condition for a period until the pressure in the evaporator rises to a point where there will be no further material drawn through the supply line 52.

In applications such as automotive air conditioning the sealed in motor may be omitted and the pump driven by a shaft extending through the wall of the receiver, or by other driving connection to an outside source of power.

While a preferred embodiment has been shown and described herein, it will be apparent to those skilled in the art that changes and modifications can be made therein without departing from the true spirit of the invention.

Having thus described the invention, what is claimed as new is:

1. A refrigeration system comprising a receiver tank, a quantity of liquid refrigerant partially filling said receiver tank, an evaporator, a supply conduit connected between the lower portion of said tank and said evaporator, a throttling device interposed in said conduit between said tank and said evaporator, a pump submerged in the liquid in said tank, a driving motor in the upper portion of said tank, a driving connection

5 between said motor and said pump, a jet nozzle, a pressure conduit extending from said pump to said jet nozzle, a housing surrounding said nozzle, a conduit extending between said evaporator and said housing, a condenser including a top and a bottom header, a plurality of cooling tubes extending between said headers, a conduit communicating said housing with said top header, a conduit communicating said bottom header with the lower portion of said tank.

2. A refrigeration system comprising a receiver tank, a quantity of liquid refrigerant partially filling said receiver tank, an evaporator, a supply conduit connected between the lower portion of said tank and said evaporator, a throttling device interposed in said conduit between said tank and said evaporator, a by-pass valve connected in shunt with said throttling device, a pump submerged in the liquid in said tank, a driving motor in the upper portion of said tank, a driving connection between said motor and said pump, a jet nozzle, a pressure conduit extending from said pump to said jet nozzle, a housing surrounding said nozzle, a conduit extending between said evaporator and said housing, a check valve interposed in said conduit between said evaporator and said housing, a return conduit extending between said housing and said tank, a condenser interposed in said return conduit.

3. A refrigeration system comprising a receiver tank, a quantity of liquid refrigerant partially filling said receiver tank, an evaporator, a supply conduit connected between the lower portion of said tank and said evaporator, a throttling device interposed in said conduit between said tank and said evaporator, a pump submerged in the liquid in said tank, a driving motor in the upper portion of said tank, a driving connection between said motor and said pump, a jet nozzle, a pressure conduit extending from said pump to said jet nozzle, a housing surrounding said nozzle, a conduit extending between said evaporator and said housing, a condenser including a top and a bottom header, a plurality of cooling tubes extending between said top and bottom headers, a conduit communicating said housing with said top header, said bottom header being inclined, the lower end of said bottom header being below the liquid level in said tank, the upper end of said bottom header being above the liquid level in said tank, a conduit communicating the lower end of said bottom header with said tank at a point below the liquid level therein.
